CLAIM

The ornamental design for an adjustable pipe joint as shown and described.

DESCRIPTION

1. Adjustable pipe joint

1.1 : Perspective, front

1.2 : Perspective, back

1.3 : Front

1.4 : Back

1.5 : Left

1.6 : Right

1.7 : Top

1.8 : Bottom

The broken lines depict portions of the adjustable pipe joint that form no part of the claimed design.

1 Claim, 8 Drawing Sheets
